CABLE END RECEPTACLE

Arthur A. Mahren, Long Island City, N. Y., assignor to Federal Telephone and Radio Corporation, New York, N. Y., a corporation of Delaware

Application September 14, 1946, Serial No. 697,108

3 Claims. (Cl. 173—328)

1

This invention relates to a cable receptacle and more particularly to a cable receptacle which is adapted to fit over the ends of a cable for test purposes such as by a so-called velocity propagation meter.

As is well known, coaxial cables include a center conductor, a layer of insulation or insulating space, then an outer conductor which may comprise a braid of conducting material and finally, an outer coating of insulation. For testing purposes the outer insulation is peeled back and the braid of the second conductor exposed. The braid and also the insulation between it if present, and the inner conductor are cut back, leaving the inner conductor and outer conductor braid exposed with the inner conductor extending beyond the outer braid. It then becomes a problem of connecting the exposed conductor ends to a cable receptacle, which in turn is connected with instruments for testing the cable.

The objects of the invention among others are: to provide a cable receptacle suitable for connecting a coaxial cable into testing apparatus; a cable receptacle adaptable to testing cables of different diameter or dual coaxial cables; a cable receptacle that allows an operator to measure the exact length of a cable; a cable receptacle that is simple and economical in construction, and is durable and long lasting; and a cable receptacle requiring no special skill on the part of an operator to assemble and install.

In carrying out the objects of the invention there is provided a cable receptacle comprising a guide sleeve of insulating material for receiving and guiding a cable therewith. A conductor element is embedded within the guide sleeve and said guide sleeve and conductor element are associated with a terminal block assembly by being connected thereto and supported thereby. The conductor element within the insulator guide sleeve may have spring fingers to insure electrical contact with a cable entered therein. The terminal block assembly may consist of a terminal insulator block within a terminal conductor block having means for securing the cable receptacle to a supporting member. The insulator guide sleeve with the conductor element mounted therein may be removably connected with and supported from the terminal conductor block as by having the conductor element in the insulator guide sleeve screw threaded into the terminal conductor block to allow interchange of different sized and single or dual cable insulator guide sleeves and conductor elements to care for different sized cables.

2

With the foregoing and other objects in view, the invention will be more fully described hereinafter and will be particularly pointed out in the claims appended hereto.

5 In the drawings, wherein like symbols refer to like, or corresponding parts throughout the several views:

Figure 1 is a perspective view of the cable receptacle shown attached to a panel with a portion thereof broken away and shown in section;

10 Figure 2 is a sectional view of the cable receptacle showing means for attaching the cable receptacle to a panel and means for attaching the parts of the cable receptacle together;

Figure 3 is another sectional view of the cable receptacle cut at a different point around the cable receptacle;

15 Figure 4 is an end view of another type of cable receptacle to receive dual coaxial cables; and

20 Figure 5 is a sectional view taken on the line 5—5 of Figure 4.

Referring to the drawings 1 represents a guide sleeve of the cable receptacle to receive and guide a coaxial cable into the cable receptacle. The 25 guide sleeve 1 is flared at 2 to guide a cable into the cable receptacle and the guide sleeve is an insulator member and is preferably made of Bakelite. A conductor element 3 is mounted within guide sleeve 1 and secured in place with 30 in guide sleeve 1 as by screws 4. As can be readily seen, conductor 3 is removable from guide sleeve 1 by withdrawal of the fastening means which may be the screws 4. The conductor member 3 is made preferably of brass but may be made of

35 any conductor metal. The conductor member 3 is screw threaded on one end thereof as by male thread 5 for mounting the insulator guide sleeve 1 and conductor member 3 to other parts of the cable receptacle and to support the insulator 40 guide sleeve 1 and conductor member 3 from a supporting means. Around the inner periphery of the conductor element 3 are spring members 6 which may be phosphorus bronze springs to improve electrical contact between a cable entered 45 into the cable receptacle and the conductor element 3. The cable receptacle also includes a terminal block assembly which is made up of a terminal conductor block 7 with a terminal insulator block 8 within the terminal conductor 50 block. The terminal insulator block 8 has a center boring 9 in the center thereof in which spring terminal 9a is threadably adjustable, the block 8 being removably attached to the terminal conductor block 7 by screws 10. The terminal conductor block 7 is screw threaded as by female

55

threads 11 to receive the male threads on conductor element 3 to thus removably secure the insulator guide sleeve 1 and conductor element 3 to the terminal conductor block 7 and terminal insulator block 8. The terminal conductor block 7 carries means 12 in the form of screws to attach the assembled cable receptacle to a supporting member such as panel 13. The terminal conductor block 7 may be of any suitable metal and copper has been used successfully. Electrical contact is established between the conductor element 3 and the terminal conductor block 7 by the screw threaded connection between threads 5 and 11. The terminal insulator member 8 may be made of a suitable insulating material and polystyrene resin has been found most satisfactory.

In operation the cable receptacle receives a coaxial cable to electrically couple the coaxial cable through the cable receptacle to suitable testing instruments. A coaxial cable is represented generally in Figure 2 in broken lines where insulation is shown removed for a short distance from inner and outer conductors of such cable with the inner conductor extending slightly (about $\frac{1}{2}$ " more or less) beyond the outer conductor. The cable is entered into the cable receptacle being guided therein by the flare 2 on insulator guide sleeve 1. The end of conductor 14 is contacted by spring members 6 on the inner periphery of conductor element 3. This effects an electrical coupling or contact between conductor 14, springs 6, conductor element 3 and terminal conductor block 7 which in turn is connected with testing instruments (not shown). The terminus of the conductor contacts the spring terminal 9a, the shank 15 of which is threaded in the central boring 9 in the terminal insulator block 8.

To care for cables of different diameter, a number of different diametered guide sleeves 1 and conductor elements 3 may be provided. The guide sleeve 1 and conductor element 3 are removable from the terminal conductor block 7 and terminal insulator block 8 by means of the screw threaded connection between conductor element 3 and terminal conductor block 7. The terminal conductor block 7 is held supported on panel 13 by screw 12 even though guide sleeve 1 and conductor element 3 are removed. The proper diametered guide sleeve 1 and conductor element 3 are selected and assembled after which the assembly is screwed into terminal conductor block 7. It is merely necessary to provide a set of guide sleeves 1 and conductor elements 3 of equal outer diameter with differing inner diameters.

Figures 4 and 5 show a modified form of cable receptacle for dual coaxial cables. The dual coaxial cable comprises two coaxial cables side by side with a conducting braid surrounding the two cables, an insulating coating being applied over the braid. The modified cable receptacle is similar in every respect to the previously described cable receptacle except that the guide sleeve 1 is different. In Figure 4 the entrance to guide sleeve 16 and the inner shape of conductor 17 for dual coaxial cables are elliptical

as shown at 18. The elliptically shaped cable opening 18 allows for the entrance of the dual coaxial cable. The elements 16, 17 and 19 may be interchangeable with elements 1, 3 and 6, respectively, within a given range of sizes.

While the invention has been described in connection with specific embodiments, it is to be understood that the same is intended as illustrative and not as limitative since other forms of the invention may be resorted to without departing from the spirit or principles hereof. The invention is rather that defined by the appended claims.

I claim:

1. A cable end receptacle comprising an insulator guide sleeve having a flaring opening in one end, a conductor element secured in said guide sleeve and having one of its ends projecting therebeyond, a terminal conductor block engaging the conductor element, a terminal insulator block secured in said terminal conductor block and a spring terminal extending through a central bore in said terminal insulator block and having end portions thereof projecting therebeyond.

2. A cable end receptacle comprising an insulator guide sleeve having a flaring opening in one end, a conductor element secured in said guide sleeve and having one of its ends projecting therebeyond, a terminal conductor block threadedly engaging the outer surface of the conductor element, a terminal insulator block secured in said terminal conductor block and being co-terminous with one end thereof and a spring terminal extending through a central bore in said terminal insulator block and having end portions thereof projecting therebeyond.

3. A cable end receptacle comprising an insulator guide sleeve having a flaring opening in one end through which a cable end is adapted to be inserted, a conductor element secured in and extending beyond the guide sleeve and provided with spring fingers around the inner periphery thereof, a terminal conductor block detachably connected to the conductor element extension, a terminal insulator block of polystyrene resin secured in the terminal conductor block and a spring terminal extending through a bore in said terminal insulator block and having one end adapted to be contacted by the cable end in the receptacle and the other end adapted to be connected to a testing device.
